UNITED STATES PATENT OFFICE.

LE ROY A. CRUMLEY, OF NEW YORK, N. Y., ASSIGNOR TO ISRAEL J. TOMBACHER AND HARRY M. FELTENSTEIN, COPARTNERS DOING BUSINESS AS M. EISENBERG & SON, OF NEW YORK, N. Y.

DESIGN FOR A LIGHTING-FIXTURE BRACKET.

Application filed May 10, 1926. Serial No. 17,632. Term of patent 3½ years.

To all whom it may concern:

Be it known that I, LE ROY A. CRUMLEY, a citizen of the United States, and a resident of the city of New York, county of Bronx, and State of New York, have invented a new, original, and ornamental Design for a Lighting-Fixture Bracket, of which the following is a specification, reference being had to the accompanying drawing, forming a part hereof.

The figure in the drawings shows a side elevational view of the lighting fixture bracket.

I claim:

The ornamental design for a lighting fixture bracket substantially as shown.

LE ROY A. CRUMLEY.
